ATTORNEY

UNITED STATES PATENT OFFICE.

WILLIAM RAROHA, OF PHILADELPHIA, PENNSYLVANIA, ASSIGNEE OF ONE-HALF TO
DOMONKOS RAROHA, OF HINSDALE, MASSACHUSETTS.

RAIL-JOINT.

1,109,178.

Specification of Letters Patent.

Patented Sept. 1, 1914.

Application filed November 12, 1913. Serial No. 800,625.

To all whom it may concern:

Be it known that I, WILLIAM RAROHA, a subject of the King of Hungary, residing at Philadelphia, in the county of Philadelphia and State of Pennsylvania, have invented 5 certain new and useful Improvements in Rail-Joints, of which the following is a specification, reference being had therein to the accompanying drawing.

10 This invention relates to rail joints, and the primary object of my invention is to provide a novel rail chair upon which the confronting ends of rails can be mounted whereby the rails can not become vertically 15 or laterally displaced.

Another object of this invention is to provide a chair with a detachable center piece that can be used as a spacer block between the ends of rails, particularly in the winter 20 time when the rails are contracted.

A further object of this invention is to provide a simple, durable and inexpensive rail chair that can be easily and quickly installed without the use of skilled labor.

25 With the above and other objects in view the invention resides in the novel construction, combination and arrangement of parts to be hereinafter specifically described and then claimed.

30 Reference will now be had to the drawing, wherein:—

Figure 1 is a side elevation of a rail joint in accordance with this invention, Fig. 2 is a plan of the same, and Fig. 3 is a cross 35 sectional view of the rail joint.

A rail chair in accordance with this invention comprises a tie plate 1 having the longitudinal edges thereof notched, as at 2 whereby spikes or other fastening means can 40 be employed for securing the tie plate to a tie or other support. Formed integral with the tie plate 1 are longitudinal parallel splice bars 3 and 4 adapted to brace the sides

of rails 5 placed in the chair, said splice bars preventing vertical and lateral displacement 45 of said rails. Arranged intermediate the ends of the splice bars is a center piece 6 that conforms in cross section to the shape of a rail and therefore represents a rail section. This rail section is used as a spacing block 50 and is retained in the chair by a screw 7 that extends through an opening 8 in the splice bar 4, through the rail section 6 and into the splice bar 3, said screw being tapped in the rail section 6 and the splice bar 3, 55 with the head of said screw countersunk in a recess 9 provided therefor in the splice bar 4.

One embodiment of the invention has been illustrated but it is to be understood that 60 the structural elements are susceptible of such variations and modifications as fall within the scope of the appended claim.

What I claim is:—

A rail chair comprising a tie plate having 65 a base portion adapted to be secured to a tie, splice bars formed integral with the base portion and adapted to brace the sides of rails and having a portion engaging the underface of the tread of a rail, a detachable 70 rail section arranged between said splice bars upon said tie plate and serving functionally as a spacer block, said rail being disposed in said chair with a base engaging the inner face thereof, and a screw extending 75 through one of said splice bars and tapped into said rail section and the other of said splice bars for detachably holding said rail section in position.

In testimony whereof I affix my signature 80 in the presence of two witnesses.

WILLIAM RAROHA.
